UNITED STATES PATENT OFFICE.

ANGELO SCARLATO, OF BROOKLYN, NEW YORK.

WINDOW DEVICE.

Application filed July 7, 1926. Serial No. 120,880.

This invention relates generally to window-frames such as are made up by the mills to be used in the construction of buildings by the building contractors. More specifically this invention pertains to a window-frame having the usual pair of vertically sliding windows and in addition thereto provides a window-frame of the usual sliding sash type with a pair of casement or French type windows. Such a combination has the advantages of both types of windows such as ease in cleaning, full openings, the ability to open any part of the window-frame to any degree; and a neat, attractive appearance.

Various attempts have been made to provide the usual sliding windows with additional inner hinged frames but windows of this type were not so favorably considered because it was not possible to open both windows simultaneously due to the overlapping of the sashes in their normally closed position. In the usual type frame the lower end of the upper sash overlaps the upper end of the lower sash, their edge surfaces being flush. A latch is mounted upon these edges for locking the sashes in their normally closed position. It is obvious then that whenever hinged windows were mounted in these sashes they could not be opened simultaneously as the lower edge of the hinged upper window would strike the upper end of the lower sash and the latch carried thereby when the two sashes were in their closed positions. Consequently only half of the entire window could be opened at one time.

To overcome these objections this invention contemplates providing means whereby the two sashes may be separated or moved beyond their normally closed position whereby both halves of the entire window may be opened simultaneously without interfering with the usual sliding structure. To accomplish this purpose the bottom sill of the usual window-frame is constructed in a new and novel manner so that a section of the sill may be adjusted to allow the lower sash to drop beyond its normally closed position a sufficient distance to allow the hinged window of the upper sash to clear the upper end of the lower sash and any latch that may be mounted thereon.

A more detailed description will be given in connection with the accompanying draw-

ings which illustrate one embodiment of this invention and in which:

Fig. 1 is a front elevation of a window-frame embodying this invention;

Fig. 2 is a section taken along line 2—2 of Fig. 1;

Fig. 3 is a section taken along line 3—3 of Fig. 1, and

Fig. 4 is a side elevation partly in section showing the two windows in open position.

In carrying out this invention the usual window-frame 1 is employed comprising generally an upper member 3; side sections 5, 5, enclosing the usual counterweights and their rigging; and bottom sill member 9. Within frame 1 there is the customary upper sash 11 and lower sash 13 which overlap at their lower and upper ends respectively and are locked in their normally closed position by a latch 15. These sashes are mounted for vertical sliding movement in frame 1 being guided and retained by the side sections 5, 5. The upper sash 11 has a subframe or sash 17 set within it and hinged thereto by hinges 19, 21 to swing upon a vertical axis and secured in closed position by a clasp 23. In a similar manner the lower sash 13 has mounted within it a subframe or sash 25 pivoted upon hinges 27, 29 and secured by a clasp 30. The usual panes of glass 31, 33 are fastened in the sub-sashes 17 and 25 respectively by any suitable means.

It is to be noticed that in the normally closed position (Figs. 1 and 2) the upper window 31 could not be opened upon the hinges due to the overlapping of the lower edge of the upper sash 17 and the upper edge of the lower sash 13. To overcome this objectionable feature the bottom sill 9 of frame 1 is constructed with a slide member 35 which acts as an abutment or jam for the lower edge of the lower sash 13. This slide 35 is movable to be retractable from a position under the sash 13 to a position out of the path of said sash as indicated in Fig. 4 so as to allow the lower sash to be moved to a position beyond its normally closed position a distance substantially equal to the width of the top end of the lower sub-sash 25 plus the height of the latch 15. This will enable the upper window 31 to be swung upon its hinges without contacting with the lower sash or latch. The slide 35 is provided with a lip 37 which extends into a channel

- 39 in the upper trimming of the sill 9, and is also supplied with two dowels 41 adapted to cooperate with sockets in the lower sash 13 to prevent the member 35 from any sliding 5 movement when the sash is in normally closed position. The side sections 5 of the frame 1 are grooved as at 43 to form a stop and a ledge to support the rear edge of slide 35 when in retracted position (Fig. 4).
- 10 From the foregoing it is apparent that the two sashes may be operated in the usual manner by sliding them vertically and securing them by means of latch 15. If it is desired to open both windows simultaneously 15 upon their hinges the lower sash is raised slightly to disengage the pins 41, slide 35 is moved rearwardly to its retracted position, and the sash lowered after which both windows may be swung upon their hinges to 20 any degree of opening desired. Thus the entire window-frame may be opened as in a casement or French window or on the other hand the windows may be slid as in the ordinary frames.
- 25 It is apparent that minor changes may be made in the embodiment herein described without departing from the spirit and scope of this invention such as the method of hinging the windows or securing the sub-sashes; therefore I define my invention in the following appended claims.
- 30 1. A combination window comprising an upper sildable sash, a lower sildable sash, a window hinged to each of said sashes and a surrounding frame comprising a top section, side members and a bottom sill including an adjustable section, said adjustable section having securing pins therein cooperating with sockets in said lower sash.
- 35 2. A combination window comprising an upper sildable sash, a lower sildable sash, a window hinged to each of said sashes, and a surrounding frame comprising a top member, upright side members, and a bottom sill member including a sildable section having positioning pins therein, said side members having guiding stops therein to position said sliding member.
- 40 3. A window frame including a sill, an

upper and a lower sash sildable in said frame, said sill forming a stop to limit downward movement of the lower sash, and means movably supported above the sill to normally prevent engagement of the lower sash with the sill and hold said lower sash in position to have its upper member overlap the lower member of the upper sash, said means when moved to disengage from the lower sash permitting the lower sash to drop below said over-lapping position.

4. A window frame including a sill, an upper and a lower sash sildable in said frame, said sill forming a stop to limit downward movement of the lower sash, means movably supported above the sill to normally prevent engagement of the lower sash with the sill and holds said lower sash in position to have its upper member overlap the lower member of the upper sash, said means when moved to disengage from the lower sash permitting the lower sash to drop below said over-lapping position, glass carrying frames pivotally mounted in said sash, the glass carrying frame of the lower sash being movable to open upon the lower sash being in its lower-most position.

5. In combination, a window frame having a sill and provided on its sides with sash guiding beads, an upper and a lower sash held in said frame and guided by said beads, a false sill supported above the first mentioned sill, said false sill being supported to slide outwardly of the frame from beneath said lower sash whereby the lower sash may move downwardly to rest on said sill, the upper member of the lower sash over-lapping the lower member of the upper sash upon closing of the window with the lower sash resting on the false sill, and glass carrying frames mounted in and hinged to said sash, the glass carrying frame of the lower sash being positioned to open upon the lower sash resting on said first sill.

In witness whereof, I hereunto subscribe my signature.

ANGELO SCARLATO.
